UNITED STATES PATENT OFFICE.

JEWELL D. BROWDER, JR., OF CANADIAN, OKLAHOMA.

ELECTRIC HEATER FOR AUTOMOBILE-RADIATORS.

1,285,013.

Specification of Letters Patent. Patented Nov. 19, 1918.

Application filed December 20, 1917. Serial No. 208,083.

To all whom it may concern:

Be it known that I, JEWELL D. BROWDER, Jr., a citizen of the United States, residing at Canadian, in the county of Pittsburg, 5 State of Oklahoma, have invented a new and useful Electric Heater for Automobile-Radiators; and I do hereby declare the following to be a full, clear, and exact description of the invention, such as will enable 10 others skilled in the art to which it appertains to make and use the same.

This invention relates to an improved electric heater for automobile radiators, and also for use in connection with elevated 15 water storage tanks, and one of the objects of the invention is to provide a device of this kind eliminating the use of a non-freezing compound.

A further object of the invention is to 20 provide a heater of this kind which avoids the drainage of the radiator, as when a non-freezing compound is employed.

A further object of the invention is the provision of a heater, adapted for use on an 25 automobile radiator, whereby a heated garage is unnecessary.

A further object of the invention is the provision of a heater that will render it much easier to start the motor in cold 30 weather, owing to warm water circulating in the water jacket of the engine.

A further object of the invention is to provide a device of this kind which is entirely automatic, and which will require no 35 regulating or adjusting after once installed.

A further object of the invention is to provide a heater that may be applied to any suitable elevated water storage tank, thereby avoiding the same freezing and the water 40 pipes from bursting.

In practical fields the details of construction may necessitate alterations falling within the scope of what is claimed.

The invention comprises further features 45 and combination of parts as hereinafter set forth shown in the drawings and claimed.

In the drawings, a single view is disclosed showing the features of the invention.

Referring more especially to the drawings, 1 designates a heating element, which in the present instance consists of a resistance coil, and which may be applied to the radiator in such a manner as to serve the best purpose in heating the radiator and the 50 water therein. If desired the heater 1 may consist of more than one coil. Leads or 55

wires 2 and 3 are connected to the heater as shown at 4 and 5, and 6 denotes a relay. This relay consists of a base 7 on which is mounted a pair of electrical magnets 8 and 9, which are spaced apart as shown and pivotally mounted on the base as shown at 10 is an armature 11. An abutment pin 12 rises upwardly from the base, and a spring 13 is connected to the armature and shown 60 at 14, and is in turn connected to a pin 15, whereby the armature is normally held against the abutment pin 12. The armature 11 is provided with a pair of contacts 16 and 17, and rising from the base 7 is a pair 65 of contacts 18 and 19. A lead or wire 20 electrically connects the electromagnets 8 and 9, and 21 a thermostat which consists of a base 22 and a post 23 rising therefrom, and a blade member 24 mounted on the post. 70 This blade or member has a terminal contact 25, while the base has a similar terminal contact 26. A second thermostat 27 is provided which consists of a base 28 and a post 29 rising therefrom. An angular arm 75 30 rises upwardly from one end of the base and is provided with an overhanging portion, in which a contact screw 31 is adjustably mounted. One end of this screw has a reduced portion 32 on which a thumb nut 80 33 is threaded. A blade or member 34 is carried by the post 29. A lead or wire 35 is connected to the blade or member 24 and the post 23 by the thumb nut 36 and is in turn connected to the contact 18. A wire 90 37 is connected to the terminal contact 26, and in turn to the contact 19. A wire 38 makes a junction at 39 with the wire 37. Said wire 38 is in turn connected to the electromagnet 9. Connected to the electromagnet 8 is a wire or lead 40 and in turn is connected to the contact screw by the thumb nut 41. The wire 3 makes a junction 42 with the lead 40, and the lead 2 is connected to the pivoted end of the armature 11 by the binding screw 43. A wire 44 makes a junction at 45 with the wire or lead 35. Extending from the battery or other suitable source of current supply 46 (to which the wire or lead 44 is connected) is a lead 100 47, which is in turn connected to the blade and the post 34 and 29 by the thumb nut 48. The thermostat 21 when installed is constructed or adjusted to operate at any desired temperature near the freezing point of 105 water, say for instance 32 or 33 degrees Fah., and the thermostat 27 is likewise ad-

justed or constructed to operate under the boiling point of water, for examples 180 or 200 degrees Fah. When the thermostat 21 operates, the circuit is closed at points or 5 contact 25 and 26, thereby closing the circuit of the relay 6 at the contacts 16, 17, 18 and 19 by attracting the armature 11, also closing the circuit of the heating element. The heating element now being in circuit with 10 the source of supply heats the water in the radiator. When the temperature rises, the thermostat 21 will respond and open the circuit as at 25 and 26, but this will not open the circuit of the relay 6, as the circuit 15 of the relay is now made through the contact 18, the battery 46, the thermostat 27, the heater 1 and back to the armature. As the heating element 1 conducts its heat to the radiator and the water therein and the sur- 20 rounding atmosphere, and when the temperature has reached the desired point for instance 180 or 200 degrees Fah., the thermostat 27 will respond to the temperature and open both the relay circuit and the circuit 25 of the heating element by the separation of the blade 34 and the screw 31. The heating device is now entirely disconnected from the source of electrical supply, and as the temperature begins to fall with the sur- 30 rounding atmosphere, the thermostat 27 will again respond and close the circuit by the contact of the member 34 with the screw 31, but since the circuit of the thermostat 21 is open at 25 and 26, and will remain so 35 until the temperature lowers near the freezing point, and at such point, the circuit of the thermostat 21 will again close at 25 and 26, consequently the aforesaid cycles of operations will be repeated. In applying the 40 heating device to automobile radiators, it may be installed in direct circuit with the storage battery, which is carried by most all automobiles, and when applied to an elevated water tank, it may be installed in circuit 45 with the usual commercial electrical supply or farm lighting plant. When applied to an elevated water storage tank, said thermostats may operate between 50 and 100 degrees Fah., as the water that is drawn 50 from such tank would not be too high in temperature, or in other words too hot. Each of the blades 24 and 34 is constructed of two strips, a brass strip and a steel strip. The blade 24 has its brass strip 24^a on the 55 bottom and the steel strip 24^b on the top. With reference to the blade 34 its strips are reversed, the brass 34^a on top and the steel 34^b on the bottom. Therefore at ordinary temperature the blade 34 of thermostat 27 60 makes contact with the screw 31, and the blade 24 of the thermostat 21 is practically straight, because its brass and steel strips at ordinary temperature, are substantially the same length. The contact of the blade 24 65 of the thermostat 21 is, therefore, out of contact with the contact 26. A reduction to freezing temperature causes the blade 24 of the thermostat 21 to bend downwardly, by reason of the brass strip 24^a on the bottom contracting more than the steel strip 24^b 70 on the top. This freezing temperature also causes the brass strip 34^a on top of blade 34 to contract, but the brass strip being on top in this instance causes the blade 34 to curve upwardly and increase its contact with 75 the screw 31. When the contacts 25 and 26 of the thermostat 21 cooperatively engage, current is supplied from the battery 46 to the blade 24 of the thermostat 27 by the wire 47, to the screw 31 over wire 40 the junction 80 42, magnets 8 and 9 over the wire 38 junction 39 wire 37 to and through the contact 25 and 26, the blade 24, the wire 35^a to the junction 45 wire 44 back to the battery 46. The magnets 8 and 9 are then energized 85 thereby attracting its armature 11, whereby the contacts 16 and 17 will co-operatively engage the contacts 18 and 19. The current over the wire 40 then has two paths, the one above mentioned and another over the wire 90 3 to the heating coil 1, then over the wire 2, the armature 11, where it divides, part passing over the wire 37 and through the thermostat 21 over the wire 35^b and the other part passes over wire 35, the two divisions 95 of the current reuniting at the junction 45 and passing back to the battery 46 by the wire 44. As the heating coil increases the temperature, the blade 24 bends upwardly and the contacts 25 and 26 separate, but the 100 magnets 8 and 9 are maintained energized, because the current leaving coil 1 (part of which previously passed over the wire 37) then all passes over wires 37 and 44, and current from magnets (which previously 105 passed through the thermostat 21) passes from wire 38 to wire 37, armature 11 and unites with current from the heating coil, passing over wires 35 and 44 to the battery 110 46. This condition continues until the blade 34 of the thermostat 27, as a result of a rise in temperature, bends downwardly and away from the screw 31, which will then open the circuit at the screw 31, until a second reduction in the temperature results in a repetition 115 of these operations.

The invention having been set forth what is claimed as new and useful is:—

In an electrical heating device for automobile radiators, a heating element consisting of a resistance coil adjacent the radiator, a relay comprising electromagnets and an armature therefor in circuit with one end of the heating element, an electrical supply, a thermostat in circuit with the supply and having electrical connections with electromagnets of the relay and electrical connection with the supply, said thermostat having make and break electrical connections with the armature of the relay and adapted to 130

operate responsive to a degree of temperature near that of freezing for closing the relay circuit, whereby the heating circuit is closed, said electrical supply being in circuit with the other end of the heating element, and a thermostat in said circuit between the supply and the heating element and having electrical connections with the electromagnets of the relay, whereby the 5 second thermostat operates at a degree of 10

temperature below that of boiling of the water in the radiator for opening the circuit between the supply and the heating element.

In testimony whereof I have signed my name to this specification in the presence of 15 two subscribing witnesses.
